UNITED STATES PATENT OFFICE

2,336,569

AIRCRAFT SPARK PLUG

Hector Rabazzana, Flint, Mich., assignor to General Motors Corporation, Detroit, Mich., a corporation of Delaware

Application October 13, 1941, Serial No. 414,746

1 Claim. (Cl. 123—169)

My invention relates to spark plugs designed to ignite the mixture of air and hydrocarbon supplied to and burned within the cylinder of an internal combustion engine, and particularly to so-called "shielded" spark plugs and to the current supply leads associated therewith; the purpose of the invention being to prevent the emanation of high frequency electro-magnetic waves and other disturbing influences, due to high tension oscillating current supplied through the leads and whereby the combustible mixture is ignited. Such oscillations if not inhibited as by suppressors of high resistance included in the supply conductors leading to the plugs, or by enclosing the leads and plugs in metallic sheaths which are grounded to the engine structure with which the plugs are used, interfere with and may prevent the proper operation radio receiving and other sensitive apparatus carried by an aircraft propelled by the engine with which the plugs are used; because of the noise due to the high tension high frequency alternating or varying current in the supply conductors leading to the spark plugs or rather, and more definitely speaking, to the central insulated electrodes of the spark plugs of the engine which propels the aircraft. The invention to which this present application relates includes various features designed to prevent the high tension current made use of as aforesaid from interfering with the proper operation of adjacent radio and like sensitive devices; and it includes the use of both a high resistance oscillation suppressor and shielding means such as is hereinbefore referred to, associated with each spark plug and with the supply conductor leading to the central insulated electrode thereof.

The drawing accompanying and forming a part of this specification illustrates the preferred form of my invention, and therein:

Figure 1 is a view showing a section of my improved spark plug upon a longitudinally extending central plane, and about three times its natural and usual size.

Figure 2 is a view showing a corrugated annular washer and a cap for holding the same in place, located at one end of a short tubular sleeve of ceramic material; there being a like cap and washer at each end of the sleeve.

Figure 3 is a view, further enlarged, showing a piece of the central insulated electrode of my improved spark plug in side elevation.

Figure 4 is a view showing a section upon a transverse plane indicated by the line 4—4, Figure 3.

Referring now to the drawing, the numeral 10

designates a hollow metallic outer shell or casing circular in cross-section and made commonly of steel, the same being externally threaded at its lower end as shown so as to screw into a correspondingly threaded spark plug opening in the cylinder of an internal combustion engine; and the numeral 11 designates a tubular shield made of steel or equivalent material and threaded at its lower end, as at 12, so as to screw into the upper end of the casing 10 as shown. This shield tube surrounds and extends above the insulating member 13 of the plug, which is supported within the casing 10, and is externally threaded as at 14 to facilitate the attachment to the shield and thus 5 to the plug casing 10 of a metallic conduit, not shown, through which the conductor or lead whereby high tension current is supplied to the insulated central electrode 15 of the plug extends. The shield 11 has a tubular lining or sleeve 16 10 made of glass, porcelain or equivalent ceramic material; and cushioning devices are provided at each end of this sleeve to protect it from injury. These cushioning devices, they being of the same construction at each end of the sleeve, comprise 15 a thin metallic ring 17 having integral depending legs 18 which grasp the ends of the sleeve and space it slightly from the interior of the shield 11, see Figure 1, and corrugated washers 19 of thin metal at the extremities of the sleeve which 20 25 may yield slightly as the shield is screwed into the shell 10; to grasp the sleeve between an inwardly extending ledge 20 at the upper end of the shield 11 and a metallic washer 21 against which the lower end of the threaded portion 12 of the shield abuts when the parts are assembled. This washer, as will be seen, supports the lower 30 one of the cushioning devices, and it engages the upper end of a resilient C-shaped spring washer 22 whereby the insulating member 13 is held in place within the casing 10 as is usual in spark 35 plug constructions.

Extending longitudinally of the insulating member 13 is a passage having a lower portion 23 through which the insulated electrode 24 of the plug extends, and a larger upper or outer portion 25 within which a high resistance oscillation suppressor 26 is housed; the two passages being separated by an internal ledge 27 which provides support for the enlarged upper end of the insulated electrode. A sealing member 28 of plastic conductive material is introduced into the passage 25 and compacted about the upper end of the electrode 24 during the manufacture of the plug to hold the electrode in place, and to prevent leakage along the electrode when the plug is in

use. A cup-shaped metallic abutment 28 is pressed into engagement with the upper end of the sealing member as the latter is pressed into engagement with the upper end of the electrode, see Figure 1. The suppressor may comprise a granular conductive material mixed with a suitable binder and molded into cylindrical form, as shown, and it is preferably provided with metallic caps 30 at its two ends. Its resistance is commonly around from 50 to 100 ohms.

The suppressor 26 is shown as held within the passage 25 in the insulating member by a restraining plug or cap member 31, having a depending tubular part 32 and struck out spring lugs 33 which spring outward and into a groove 34 within and adjacent the upper end of the insulator 13 as the tubular part 32 of the cap member is pressed into the passage 25, thus providing an interlocking connection between the cap and the upper end of the insulating member; and a spring 35 is interposed between the cap member and the upper end of the suppressor. The conductor or lead through which current is supplied to the plug contacts with the cap 31, so that current flows through the spring 35 and the suppressor 26 to the insulated electrode 24 as will be understood.

The electrode 24 comprises a central copper core which provides a heat conducting path of low resistance from the spark gap at the lower end of the plug upward therefrom, and a sheath 36 of nickel alloy enclosing said core and protecting the electrode from injury by the high temperature gases within the combustion chamber; and the sheath 36 is shown as provided with a circumferentially arranged series of projections 37 formed, for example, by knurling the sheath; and the purpose of which is to space the electrode centrally within the passage 23 and prevent the same from coming into violent contact with the interior of said passage; which might otherwise occur with consequent breaking of the lower end of the insulator if the plug is subjected to inordinately severe shocks when in use, or during the installation of the plug in the engine with which it is used.

The capacity associated with the ignition device or system herein contemplated is dependent upon the structural features thereof and, in the arrangement herein, depends for the most part and in fact substantially entirely upon a condenser provided by the central insulated electrode of the plug, and the tubular grounded metallic shield and the shell thereof. The energy stored by this condenser is dependent upon the voltage of the supply current and the distance these elements are spaced apart from one another, and the stored energy is discharged across the spark gap of the plug.

Assuming a maximum value of 5000 volts in the conductor leading to the spark plug, and a resistance of five ohms at the spark gap after the flow

between the electrodes has been initiated, the current flow in the ignition circuit would be 1000 amperes. This, of course, is very much greater than is required to effect ignition of the combustible mixture and, while the excess of current might perhaps be condoned as it is in the nature of an instantaneous surge of extremely short duration, and the energy loss is small, such a large current flowing but for an instant would 10 wear the electrodes away rapidly. When, however, a suppressor having a resistance of around 95 ohms is included in the ignition lead the current flow, assuming the same 5000 voltage, will be 50 amperes; which will be abundant to accomplish 15 ignition of the combustible mixture, and will at the same time very much lessen the wear or erosion of the electrodes.

Suppressors similar to the element 26 have heretofore been used in the high tension supply 20 conductors leading to the insulated electrodes of spark plugs but they have commonly been of high resistance, usually around 10,000 ohms, with the result that the current supplied to the electrode has been very much reduced (it would be half 25 an ampere in the not unusual case assumed); whereas when a suppressor having a resistance on the order of from 50 to 100 ohms is used the current will insure proper ignition of the combustible mixture, but will not be great enough 30 to cause excessive wear and erosion of the electrodes.

Having thus described and explained my invention I claim and desire to secure by Letters Patent:

35 In a spark plug of the class described, a hollow casing threaded at its lower end; an insulating member supported within said casing and having a passage extending longitudinally therethrough; an insulated electrode within the inner end of 40 said passage and terminating adjacent a second electrode at the inner end of said casing; an oscillation suppressor within the upper end of said passage and through which current flows to said insulated electrode; a cap member interlocked with the upper end of said insulating member for retaining said suppressor in place within the passage aforesaid; a spring interposed between the upper end of said oscillation suppressor and said cap member and acting to force 45 said suppressor downward, to thereby maintain a yieldable contact between the lower end of said oscillation suppressor and said insulated electrode; a tubular metallic shield extending upward from said hollow casing beyond the upper end of said insulating member, and which shield surrounds the upper end of said insulating member, said cap member, and said spring; and a tubular sleeve of ceramic material within said metallic shield and enclosing the upper end of 50 said insulating member.

HECTOR RABEZZANA.
